MICROPHONE HOUSING

Frank C. Jahn, Mineola, N.Y., assignor to Intelex Systems Incorporated, New York, N.Y., a corporation of Delaware

Application October 30, 1958, Serial No. 53,206

Term of patent 14 years

(Cl. D26—14)

FIG. 1

FIG. 2

FIG. 3

FIG. 5

FIG. 6

FIG. 4

Fig. 1 is a perspective view of a microphone housing, showing my new design;

Fig. 2 is a top plan view;

Fig. 3 is a front elevational view;

Fig. 4 is a bottom plan view with the hinged stand folded against the housing;

Fig. 5 is a side elevational view, the opposite side being substantially a mirror image thereof; and

Fig. 6 is a rear elevational view thereof.

I claim:

The ornamental design for a microphone housing, as shown and described.
